UNITED STATES PATENT OFFICE.

ENOS B. HIATT, OF PALISADE, COLORADO.

DEVICE FOR PACKING FRUIT AND THE LIKE.

Application filed September 27, 1924. Serial No. 740,280.

To all whom it may concern:

Be it known that I, ENOS B. HIATT, a citizen of the United States, residing at Palisade, in the county of Mesa and State of Colorado, have invented certain new and useful Improvements in Devices for Packing Fruit and the like, of which the following is a specification, reference being had to the accompanying drawings.

10 This invention relates to a device and means for packing fruit and the like and it is an object of the invention to provide a novel and improved means whereby the fruit or the like may be packed in a manner 15 whereby the top layer may be placed permanently in regular form and position and maintained in such position.

Another object of the invention is to provide a novel and improved means whereby 20 the fruit or the like when packed is protected from injury when in transit and wherein the surface of the contents comes in perfect contact with the permanent lid of the container.

25 An additional object of the invention is to provide novel and improved means for packing fruit and the like wherein a temporary reinforcing shell is employed during the process of packing.

30 The invention consists in the details of construction and in the combination and arrangement of the several parts of my improved method and device for packing fruit and the like whereby certain important advantages are attained and the device rendered simpler, less expensive and otherwise 35 more convenient and advantageous for use, as will be hereinafter more fully set forth.

The novel features of my invention will 40 hereinafter be definitely claimed.

In order that my invention may be the better understood, I will now proceed to describe the same with reference to the accompanying drawings, wherein:—

45 Figure 1 is a view partly in elevation and partly in section illustrating a package accomplished in accordance with an embodiment of my invention;

Figure 2 is a view in top plan of the mem- 50 ber initially employed;

Figure 3 is a cross sectional view taken through Figure 2;

Figure 4 is a view similar to Figure 3 illustrating another embodiment of such member;

Figure 5 is a view partly in section and partly in elevation illustrating certain of the steps employed in my improved method;

Figure 6 is a view partly in elevation and partly in section illustrating an additional 60 step in the method, the container proper being diagrammatically indicated by broken lines;

Figure 7 is a cross sectional view taken through the removable reinforcing shell; 65

Figure 8 is a view in top plan of a still further modified form of member.

As disclosed in the accompanying drawings, C denotes a permanent container of a conventional type and which is adapted to 70 have its top or open face closed by a lid L.

In packing fruit or the like in the base container C, the member A which is herein disclosed as substantially concavo convex, is first placed on a suitable support with its concave face upwardly disposed. This concave face of the member A is provided with the corrugations or indentations 1, herein disclosed as arranged in concentric circles 75 although I do not wish to be understood as 80 limiting myself in this respect.

The fruit or the like such as apples, oranges, peaches, etc., are laid in these corrugations or indentations 1 whereby a firm basis is formed for the following layers. 85 The jacket or liner B preferably of pasteboard and of requisite dimensions is set within the reinforcing shell D, said jacket being of suitable material possessing the requisite strength and serves to hold the 90 jacket or liner B temporarily. The assembled jackets B and D are placed on the under rim 2 of the member A and said jacket or liner B is entirely filled with the 95 fruit or the like.

The reinforcing shell D is then removed and the container C is disposed over the jacket or liner B whereupon the container C, jacket B together with the member A are inverted to normal position, that is, 100 with the member A on top of the container C. The member A is then removed and the lid L applied and the process of packing is completed.

In packing fruit or the like in accordance with the invention hereinbefore described, means are provided whereby the top layer of the fruit may be placed in desired or regular form and position and retained therein. 110 The contents of the container C are also

protected from injury in transit as the outer layer of fruit or the like will have perfect contact with the lid L.

The jacket or liner B within the container 5 C protects the contents from injury as the result of direct contact with the inner wall of the container C and to further assure the efficiency of the packed container I find it of advantage to provide said jacket or liner 10 B with the vent holes 3.

As illustrated in Figure 4, the member A' has its upper concave face substantially smooth and unobstructed as under certain 15 conditions it is not required that said concave face be corrugated or indented since some varieties of fruits are somewhat flattened and will of themselves lie in place.

As illustrated in Figure 8, the member A'' is provided in its upper face with the 20 pockets 4 which may be employed in place of the corrugations 1 hereinbefore referred to.

It is also to be understood that at all times it is not necessary to provide the jacket or liner B with the vent holes as shown but 25 these openings 3 may be used according to the requirements for ventilation of the articles to be shipped.

While I have hereinbefore stated that the jacket or liner B is constructed of paste- 30 board it is to be understood that any desired material may be employed which provides a relatively weak walled jacket or liner and as disclosed in the accompanying drawings, the reinforcing shell D and the jacket or liner B are of substantially the same 35 length.

I claim:—

1. An apparatus for packing fruit, including a facing base, a relatively weak walled basket liner and a reinforcing shell therefor adapted to be placed on the facing base, said shell being outermost and designed 40

for removal preparatory to telescoping the basket to be filled over the filled liner, said liner being of such size to receive the full 45 content of the basket to be filled.

2. An apparatus for packing fruit, including a facing base, a basket liner and a reinforcing shell therefor adapted to be placed on the facing base, said shell being outermost and designed for removal 50 preparatory to telescoping the basket to be filled over the filler liner, the facing base being provided with means for properly positioning the shell and liner thereon.

3. An apparatus for packing fruit, including a facing base, a relatively weak walled basket liner and a reinforcing shell therefor adapted to be placed on the facing base, said shell being outermost and designed for removal 55 preparatory to telescoping the basket to be filled over the filling liner, the liner and reinforcing shell being of substantially the same length.

4. Means for packing fruit including a 60 charge forming apparatus comprising, a reinforcing shell and a relatively weak walled liner one fitting in the other, both of substantially the same length and of a form to approximate the internal dimensions of the 65 receptacle to be filled.

5. An apparatus for packing fruit, including a facing base, a relatively weak walled endless basket liner and a reinforcing shell therefor adapted to be placed on the facing 70 base, said shell being outermost and designed for removal preparatory to telescoping the basket to be filled over the filler liner, the liner and reinforcing shell being 75 of substantially the same length.

In testimony whereof I hereunto affix my signature.

ENOS B. HIATT.
